UNITED STATES PATENT OFFICE.

WILLIAM GEORGE KIRKLEY BIRKINSHAW, OF WOLVERHAMPTON, AND CLAUDE ARTHUR BROWN, OF SYSTON, ENGLAND.

CONSTRUCTION OF PROMENADES AND PLAYING-COURTS.

1,140,241.

Specification of Letters Patent. Patented May 18, 1915.

Application filed February 18, 1914. Serial No. 819,566.

To all whom it may concern:

Be it known that we, WILLIAM GEORGE KIRKLEY BIRKINSHAW and CLAUDE ARTHUR BROWN, subjects of the King of Great Britain, residing, respectively, at Wolverhampton, in the county of Stafford, England, and Syston, in the county of Leicester, England, have invented certain new and useful Improvements Relating to the Construction of Promenades and Playing-Courts, of which the following is a specification.

Our invention relates principally to the construction of playing courts for the games of lawn tennis, tennis, racket, badminton, bowls, fives and the like, but is also applicable to the construction of promenades generally such for example as play grounds, garden paths, athletic and drilling grounds, and in fact to any open spaces where a firm set and practically dustless surface for foot passengers is desired.

The accompanying drawing is a sectional view, near one edge, of a playing court constructed according to our invention.

According to our invention the ground or site on which the promenade or the like is to be constructed is, if the existing conformation of the site renders it necessary, suitably excavated or leveled. The bottom level of the site, in the event of the soil being of a heavy nature is drained by a system of main and branch drain pipes, or by means of a layer of clinkers. Such drainage is however not required where the soil or sub-soil is of a naturally open or porous character, such for example as sand or gravel.

The bottom layer *a* of material which we employ consists of unscreened ashes of a thickness of about three inches. This is well rolled and on the top of the same we put a layer *b* of one and a half inches of screened ashes obtained by passing the said ashes over a screen of a half to three quarter inch mesh. This layer is also well rolled and the surface is afterward raked. On this prepared ash surface we place a layer *c* of three quarters of an inch or thereabout of burnt and screened brick earth, preferably burnt boulder clay and marl in combination, the said burnt brick earth being

crushed and screened by passing it over a screen of a quarter of an inch mesh or thereabout. This material is then sprinkled with powdered calcium chlorid or other deliquescent substance and is left for some hours, after which it is well watered and again rolled. Or the material may be watered with a solution of the deliquescent substance to be used. The final treatment consists in dusting the surface obtained with fine burnt brick earth the material employed being preferably that blown by a fan through a screen of one sixteenth of an inch mesh. The surface of burnt brick earth and calcium chlorid is indicated in the drawing by the reference character *d*. From six to ten dressings of the fine powdered burnt brick earth are given the surface being thoroughly watered and well rolled after each dressing and a dressing of calcium chlorid or other deliquescent substance may be employed after or with one or more of the dressings of fine burnt brick earth.

By the process hereinbefore described a very firm and smooth surface is obtained which can be repaired or renewed from time to time by applying a dressing of the fine powdered burnt brick earth the renewed or repaired surface being sprinkled with the powdered deliquescent substance and afterward watered and rolled or being watered with a solution of the deliquescent substance. To prevent the encroachment of vegetation from the surrounding soil *f*, a border *e* of suitable material, such as brick or concrete, may be provided.

We claim,—

The herein-described process of constructing playing grounds which consists in successively applying to the surface of the selected site a layer of unscreened ashes of a thickness or depth of about three inches, a layer of screened ashes of a thickness or depth of about one and a half inches obtained by passing the said ashes over a screen of a half to three quarter inch mesh and a layer of screened burnt brick earth of a thickness or depth of about three quarters of an inch, the said brick earth being screened in a sieve of a quarter to an inch mesh or thereabouts, applying a dressing of

deliquescent substance to the last named layer, and finally applying a dressing of powdered burnt brick earth to the surface thus dressed, the material for the last named dressing being preferably obtained by blowing the material through a sieve of one sixteenth of an inch mesh.

In testimony whereof we have hereunto

set our hands in presence of two subscribing witnesses.

WILLIAM GEORGE KIRKLEY BIRKINSHAW.
CLAUDE ARTHUR BROWN.
